UNITED STATES PATENT OFFICE.

OTTO LEONARD RAABE AND ARTHUR TERREY, OF HAYES, ENGLAND, ASSIGNORS TO THE GOSS PRINTING PRESS COMPANY, OF CHICAGO, ILLINOIS, A CORPORATION OF ILLINOIS.

PRINTING-MACHINE.

1,111,321.

Specification of Letters Patent. Patented Sept. 22, 1914.

Application filed April 23, 1913. Serial No. 763,010.

To all whom it may concern:

Be it known that we, OTTO LEONARD RAABE, a citizen of the United States of America, and ARTHUR TERREY, a subject of the King of Great Britain, both residing at Hayes, in the county of Middlesex, England, have invented new and useful Improvements in or Relating to Printing-Machines, of which the following is a specification.

This invention relates to printing machines of the type in which the paper for printing is supplied from a continuous web or reel placed between or under the printing mechanism of the machine.

It is customary with this type of printing machine to provide a single reel of paper rotatably mounted in a wheeled trolley or carriage which is adapted to be moved to and from its position between or under the printing mechanism of the machine so that when the reel of paper becomes exhausted, the carriage can be withdrawn and after having been provided with a fresh reel can be reintroduced into the machine. These operations not only involve heavy manual labor but occupy a good deal of time during which the printing machine remains idle.

The chief objects of our invention are to provide in connection with printing mechanism of this type a full spare reel in such a position that it may be quickly attached to the end of the paper severed from the exhausted reel, so that the press works in a practically continuous manner and to provide means to avoid the heavy manual labor above stated.

According to our invention we provide each printing section of the machine with two reel carriages which are adapted to be withdrawn and replaced alternately along suitable guides or rails so that while the reel of one carriage is supplying paper to the machine the other carriage can be withdrawn to receive a new reel and replaced ready for use when the other reel becomes exhausted, without interrupting the working of the machine.

The movement of the reel carriage to and from the machine and the lifting of the reels to and from the withdrawn carriages, are performed by mechanical means preferably operated hydraulically or pneumatically. The actuation of the usual tension

brakes and the usual side adjustment mechanism is also preferably effected by mechanical means which may also be operated hydraulically or in any other suitable manner.

The machine is also preferably so constructed and arranged that the various operations above stated can be effected from the floor level at the base of the machine, that is to say without requiring deep pits to be formed beneath the machine for the accommodation of the reel carriage and the parts coöperating therewith.

In order that the said invention may be clearly understood and readily carried into effect, the same will be described more fully with reference to the accompanying drawings, in which:—

Figure 1 is a diagrammatic view of a printing machine showing the working position of the various paper reels and their carriages relatively to the printing sections of the machine. Figs. 2, 3 and 4 are general views showing one example of the means employed for moving the reel-carriages to and from the machine, and lifting the reels to and from the withdrawn carriage; Fig. 2 being a sectional front elevation; Fig. 3 a plan and Fig. 4 a sectional side elevation. Figs. 5 and 6 are enlarged views of portions of Figs. 2 and 4 illustrating certain details which are not shown in the last mentioned figures. Fig. 7 is a sectional elevation showing the hydraulic control gear for moving the reel carriages to and from the printing machine; Fig. 8 is a sectional elevation of the carriage control valve; Fig. 9 is a sectional elevation showing the paper reel lifts and the hydraulic control gear therefor.

A A are the various printing sections of the machine and B B the two reel carriages for each section, C C are rails extending laterally from the printing machine to the re-loading point, D D are the reels of paper which are mounted in the said carriages B B; E E are lifts situated at the re-loading point for the purpose of receiving the expended reels from the carriages and lowering them to the floor level and for elevating fresh reels into them. The said reel carriages are each provided with flanged or grooved wheels b adapted to run along the said rails C C which are situated slightly below the level of the floor G.

In the example shown we effect the move-

ment of the carriages to and from the printing machine by hydraulic power for which purpose the said carriages are provided with hydraulic cylinders b' , the rams b^2 of which 5 are rigidly supported at their outer ends so that they are stationary and the cylinders slide thereon in moving the carriages, suitable valves hereinafter described being provided to control the flow of the motive fluid 10 to and from the cylinders. The reels D are furnished with spindles d adapted to be supported in recesses or bearings formed in standards or supports B in which the reels are free to revolve. The said standards 15 have lateral projections b^3 (Fig. 5) along which the said spindles can be rolled in moving the reels to and from their bearings during the transference of the said reels from the lifts E to the carriages, or 20 from the carriage to the said lifts. These lifts are in the example shown operated hydraulically for which purpose each lift comprises a pair of vertically arranged rams e having a horizontal platform at their 25 upper ends and working in cylinders e' which are provided with suitable valves as hereinafter described for controlling the rise and fall of the platform. When in the lowered position the platform lies flush with 30 the floor G.

For the purpose of controlling the carriages hydraulically, each of the cylinders is provided with a valve K, which, in the example shown by Figs. 7 and 8, is of the 35 rotary kind comprising a cylindrical casing having in its periphery an exhaust port k' and two pressure ports k^2 , k^3 connected to the opposite ends of the cylinder b' by the pipes k^4 , k^{4x} (Fig. 7). Within the said valve 40 casing is an angularly displaceable valve member K' having in it a hollow central passage k^5 to which the motive fluid is led by suitable pipes, and having also a radial passage k^6 adapted to communicate with 45 either of the pressure ports k^2 , k^3 in accordance with the position of the valve member K', the arrangement of the pressure ports and the exhaust port being such that when the said radial passage k^6 communicates 50 with one of the pressure ports the other is in communication with the exhaust port. In order that the movement of the carriage may control the said valve, the aforesaid valve member is provided with a boss ex- 55 tending through the casing and carrying an arm k^7 adapted to coöperate with two stops H, H' carried on a longitudinally displaceable rod H^2 connected to a suitable hand lever H^3 situated at a convenient part of the 60 machine so that the said rod can be actuated at will to the extent limited by the collars H^4 , H^5 fixed thereon.

As shown in Fig. 7, the reel carriage is about to leave the printing machine and 65 move outward toward the right in the

direction of the arrow. To effect this, the hand lever H^3 is moved toward the right as shown by the full lines whereby the rod H^2 is shifted in a direction to cause the stop H' to move the valve arm k^7 into the 70 position 2 indicated in Fig. 8 so that the passage k^6 in the valve member K' communicates with the pressure port k^3 and places the other port k^2 to exhaust, thereby allowing the motive fluid to flow through 75 the pipe k^{4x} into the right hand end of the cylinder b' and causing the said cylinder together with the carriage to be moved to the right. As the carriage approaches the 80 termination of this movement, the valve arm k^7 comes into contact with the stop H which is rendered stationary in this direction by the collar H^4 bearing against its abutment H^5 , with the result that the arm k^7 is moved into the vertical position shown by the full 85 lines in Fig. 8 thereby placing the valve member in a position to cut off the motive fluid and bring the carriage to rest.

When it is required to return the carriage to the printing machine, the hand lever H^3 is moved over to the extreme left 90 causing the shaft H^2 and the stop H to be moved also to the left and the collar H^5 to abut against the end wall of the recess in which the rails C are situated, with the result that the valve arm is moved into the 95 position 3 indicated in Fig. 8. The passage k^6 in the valve member K' then communicates with the pressure port k^2 , with the port k^3 in position to exhaust, thereby allowing the motive fluid to flow through the 100 pipe k^4 into the left hand end of the cylinder b' and causing the said cylinder together with the carriage to be returned to the printing machine. The carriage is brought to 105 rest by the valve arm k^7 coming into contact with the stop H' which is rendered stationary in this direction by reason of the collar H^4 bearing against its abutment. The effect of the valve arm coming against 110 the stop H' is to cause the said arm to be moved back again into the vertical position shown by the full lines in Fig. 8 thereby placing the valve member in a position to 115 cut off the motive fluid.

When it is again required to withdraw the carriage, the hand lever H^3 is moved back to the right and the cycle of operations again takes place as above described. It will of course be understood that the pressure pipe communicating with the central passage k^5 in the member K' and the exhaust pipe leading from the exhaust port k' in the valve casing must be of a flexible character.

The rams of the lifts e' for raising and lowering the platforms E are controlled by a valve L, Fig. 9, which is somewhat similar in construction to the carriage control valve K. The casing of this valve has a 120

port which communicates by means of the pipes l , l' with the lower ends of the two lift cylinders, and also a port communicating with the exhaust pipe l^2 . The fluid under pressure is supplied through a pipe l^3 communicating with the central opening in the movable valve member whose radial passage can be brought by a proper manipulation of the hand lever l^4 , into register with the port communicating with the pipes l , l' when it is desired to elevate the lifts for raising the platform E. When the said platform E is to be lowered, the valve member is moved by the lever l^4 into a position in which the port communicating with the pipes l , l' leading to the lift cylinders communicates with the exhaust pipe l^2 so that the lifts descend under the action of gravity.

Carried on the inner side frame a of the printing machine are the usual tension brake pulleys F (Figs. 5 and 6) which are so positioned as to lie opposite the said spindles d of the reels to engage therewith when the latter are in position in the machine, the said brake pulleys being formed with cylindrical extensions f which are mounted in bushes f' in the side frame a and held rotatably therein by a collar f^2 secured to the free end of the cylindrical extension where it projects through the frame. The brake pulleys thus remain in the frame of the printing machine when the carriages are removed. The inner ends of the spindles d are of rectangular shape in cross section to fit into correspondingly shaped axial holes in the brake pulleys when the carriages are in place in the machine, whereby the said spindles and their reels revolve together with the brake pulleys.

The brake pulleys are each provided with a brake shoe in the form of a divided, wood-lined metal band f^4 attached to the machine frame by bolts f^5 and extending around the periphery of the brake pulleys F. Each brake shoe is under the control of a small hydraulic or compressed air cylinder f^6 the piston of which operates through suitable mechanism comprising a bell crank lever f^7 , to exert the necessary degree of pressure upon the brake pulley for obtaining the required tension on the paper supplied to the printing machine from the reel.

For the purpose of locking the carriages in position in the machine each carriage is provided with a pivoted latch lever b^4 (Fig. 6) adapted to slide up the inclined or conical surface of a projection or head a^2 mounted in the machine frame a . On reaching the summit of the said inclined or conical surface a tooth or projection b^5 on the latch b^4 falls into a recess a^3 behind the conical head a^2 thereby locking the carriage in place. To permit of side adjustment of the reels (that is to say adjustment of the distance between the side frame of the machine and

the adjacent ends of the reels) the said conical head a^2 is provided with a screw threaded body or stem a^4 which engages a correspondingly threaded sleeve carried by the machine frame, means being provided whereby it can be conveniently rotated as for example by a sprocket wheel a^5 operated by an endless chain carried by another sprocket wheel situated at some convenient point on the machine. On rotating these sprocket wheels by suitable means, the said projection or head a^2 will be caused to project to a greater or lesser extent from the machine frame. To liberate the carriage prior to its withdrawal from the machine, a toe piece f^8 forming part of a rod f^9 is adapted to lie under the free end of each latch lever, so that by lifting the rod, the toe piece will lift the latch lever and disengage the latter so that the carriage is then free to be withdrawn. The said rod f^9 is shown as forming part of the plunger or piston of the aforesaid brake operating cylinder f^6 , so that the releasing of the carriage can be performed mechanically and simultaneously with the release of the tension brake. When a fresh reel is being placed in position its spindle engages with the brake pulley before the latch lever b^4 comes into engagement with the recess a^3 . The rod f^9 may then be permitted to descend thereby applying the tension brake without ill effect and at the same time enabling its toe piece f^8 to come under the latch lever b^4 ready for the next releasing operation.

When one of the reels is becoming exhausted, its web of paper is severed from its adjacent machine section and the web of the contiguous reel is connected by gluing or other suitable means to the severed end of the paper in the machine section and the machine is slowly started until the said joined end has passed into the machine section the new reel being meanwhile assisted to revolve by the operator so as to relieve the connection of the old web with the paper on the new reel from undue strain. The carriage of the exhausted reel is then disconnected from the machine frame by the liberation of the latch lever b^4 , and the said carriage withdrawn by means of the hydraulic cylinder and ram b , b^2 to the reloading point as already explained (see Figs. 3 and 4). The paper reel lift is then raised into a suitable position to receive the exhausted reel which is rolled out of the said carriage on to the table or platform E of the lift. The lift is then lowered to the floor level and the exhausted reel rolled away and replaced by a fresh one. The fresh reel is then raised by the lift to the necessary extent to bring its spindle into a position to be rolled along the lateral projection b^3 of the carriage into the bearings in the standards B, these various operations of

- the lift being effected by the control gear above described with reference to Fig. 9. After the fresh reel has been placed in the carriage the latter is pushed back again into position in the printing machine by its hydraulic cylinder as above described and after becoming locked in place by the latch lever b^4 is ready to supply the machine with paper when the contiguous reel becomes exhausted. By placing a lift between each pair of rails C C as aforesaid we make one lift capable of serving either one of the two carriages belonging to a particular printing section.
15. As each printing section of the machine is provided with two carriages each arranged to contain a reel of paper, it will be seen that as soon as the reel of one carriage has been exhausted the other reel is ready 20 to be at once used for supplying paper to the machine without causing any appreciable delay in the working thereof; the carriage containing the exhausted reel can then be withdrawn, replenished with a fresh reel 25 and returned to the printing machine ready for immediate use when required.
- Although we have described our invention 30 in connection with hydraulic apparatus for actuating the reel carriages, the lifts and other parts we wish it to be understood that we do not desire to limit ourselves thereto except as hereinafter specifically claimed, as the various movements may be performed in any other appropriate manner.
35. What we claim and desire to secure by Letters Patent of the United States is:—
1. In a printing machine, the combination of a frame, a printing couple mounted thereon, two carriages movable laterally 40 into and out of operative position relative to said printing couple, and means carried by each of said carriages for supporting a roll of paper thereon during the printing operation for feeding the web to said printing couple.
  2. In a printing machine, the combination of a frame, a printing couple mounted thereon, two sets of rails extending laterally 50 of such machine, two carriages each movable along one set of rails into and out of operative position relative to said printing couple, and means carried by each of said carriages for supporting a roll of paper thereon during the printing operation for feeding the web to said printing couple.
  3. In a printing machine, the combination with two reel carriages for each printing section adapted to support the reels during the printing operation in position for 60 feeding the web to the printing means, of hydraulic means whereby said carriages can be withdrawn and replaced alternately and means whereby the pressure fluid to the hydraulic means is automatically cut off as the 65 carriages complete their movement.

4. In a printing machine, the combination with two reel carriages for each printing section, adapted to support the reels during the printing operation in position for feeding the web to the printing means, of guides or rails extending from said sections to a re-loading position, means whereby the carriages can be alternately moved along said guides or rails to and from the printing sections and the re-loading position, and means at the re-loading position for moving the reels to and from the said carriages. 70

5. In a printing machine, the combination with two reel carriages for each printing section, adapted to support the reels during the printing operation in position for feeding the web to the printing means, of guides or rails situated at the floor level of the machine and extending from said sections to a reloading position also situated at the floor level of the machine, means whereby the carriages can be alternately moved along said guides or rails to and from the printing sections and the re-loading 80 position, and lifts at the re-loading position for raising and lowering the reels to and from the carriages. 85

6. In a printing machine, the combination with two reel carriages for each printing section, adapted to support the reels during the printing operation in position for feeding the web to the printing means, of guides or rails situated at the floor level of the machine and extending laterally from 95 said sections to a re-loading position also situated at the floor level of the machine, means whereby the carriages can be alternately moved along said guides or rails to and from the printing sections and the re-loading position, lifts at the reloading position for raising and lowering the reels to and from the carriages, and means whereby the said carriages are automatically brought to rest on reaching the reloading position. 100

7. In a printing machine, the combination with two reel carriages for each printing section, of guides or rails situated at the floor level of the machine and extending from said sections to a re-loading position 105 also situated at the floor level of the machine, valve controlled hydraulic presses for moving the carriages alternately along said guides or rails to and from the printing sections and the re-loading position, hydraulic lifts at the re-loading position for raising and lowering the reels to and from the carriages and means for enabling said reels to be transferred laterally from the lifts to the carriages and vice versa. 110

8. In a printing machine, the combination of a frame, a printing couple mounted thereon, a carriage movable laterally into and out of operative position relative to said printing couple, means carried by said 120

carriage for supporting a roll of paper thereon for use with said printing couple, and means carried by said frame adapted to be automatically engaged by said paper supporting means as said carriage is moved into operative position relative to said printing couple for braking the rotation of said roll.

9. In a printing machine, the combination of a frame, a printing couple mounted thereon, a carriage movable laterally into and out of operative position relative to said printing couple, means carried by said carriage for supporting the roll of paper thereon for use with said printing couple, 10 a tension brake pulley mounted on said frame, a brake shoe mounted on said frame in operative relation to said brake pulley, and automatically-acting means serving to operatively connect said brake pulley with 15 said roll of paper as said carriage is moved into operative position relative to said printing couple.

10. In a printing machine, the combination of a frame, a printing couple mounted thereon, a carriage movable laterally into and out of operative position relative to said printing couple, a paper roll spindle carried by said carriage for supporting a roll of paper on said carriage, a tension 20 brake pulley mounted on said frame, and a brake shoe mounted on said frame in operative relation to said brake pulley, said spindle being adapted to enter a suitable socket in said brake pulley as said carriage 25 is moved into operative position relative to said printing couple.

11. In a printing machine, the combination of a frame, a printing couple mounted thereon, a carriage movable laterally into and out of operative position relative to 30 said printing couple, means carried by said carriage for supporting a roll of paper thereon for use with said printing couple, means carried by said frame adapted to be 35 automatically engaged by said paper supporting means as said carriage is moved into operative position relative to said printing couple for braking the rotation of said roll, means for locking said carriage in 40 operative position, and means for adjusting 45 said locking means for adjusting the engagement of said roll supporting means with said braking means.

12. In a printing machine, the combination of a frame, a printing couple mounted thereon, means for supporting a roll of paper in operative position relative to said printing couple and for moving the roll laterally relative to the machine, and braking 50 means carried by said frame adapted to be removably connected with said roll for braking its rotation while supported by said laterally-movable supporting means in 55 position for feeding the web to the printing couple for the printing operation.

13. In a printing machine, the combination of a frame, a printing couple mounted thereon, means for supporting a roll of paper in operative position relative to said printing couple and for moving the same laterally of the machine, other means for supporting a second roll of paper in operative position relative to said printing couple and for moving it laterally of the machine, and braking devices carried by 70 said frame adapted to be removably connected with said rolls of paper respectively for braking their rotation while supported by said laterally-movable supporting means in position for feeding the web to the printing couple for the printing operation.

14. In a printing machine, the combination with two reel carriages for each printing section, of means whereby said carriages can be withdrawn and replaced alternately, 75 and means whereby said carriages are mechanically locked and unlocked to and from the side frame of the printing machine when said carriages are in working position in the machine.

15. In a printing machine, the combination with two reel carriages for each printing section, of means whereby said carriages can be withdrawn and replaced alternately, 80 a pivoted latch lever on each reel carriage, 90 an inclined or conical projection on the machine frame, and means whereby the said pivoted latch lever is caused to engage with said inclined or conical projection for locking the reel carriages in position in the 100 machine.

16. In a printing machine, the combination with two reel carriages for each printing section, of means whereby said carriages can be withdrawn and replaced alternately, 105 devices for locking and unlocking said carriages to and from the side frame of the printing machine, and means for setting said devices to properly adjust the carriages in the machine.

17. In a printing machine, the combination with two reel carriages for each printing section, of means whereby said carriages can be withdrawn and replaced alternately, 115 tension brake pulleys on the spindles of the reels, brake shoes mounted on the frame of the machine and cooperating with the said pulleys, and means whereby the pulleys and the reel spindles become engaged or disengaged in the act of introducing or withdrawing the reel carriages to or from their working position in the printing machine.

18. In a printing machine, the combination with two reel carriages for each printing section, of means whereby said carriages can be withdrawn and replaced alternately, 120 tension brake pulleys revolvably mounted on said frame and adapted to be engaged by the spindles of the reels while in position upon said carriages, brake shoes mounted 125

on the frame of the machine and coöperating with the said pulleys and means whereby the pressure of the brake shoes on the pulleys is controlled mechanically.

- 5 19. In a printing machine, the combination with two reel carriages for each printing section, of means whereby said carriage can be withdrawn and replaced alternately, tension brake pulleys revolubly mounted on
10 said frame and adapted to be engaged by the spindles of the reels while in position upon said carriages, mechanically operated brake shoes coöperating with said pulleys, locking devices for retaining the carriages
15 in their working position in the machine, and means whereby the actuation of the brake shoes automatically operates said locking devices.
20. In a printing machine, the combination with two reel carriages for each printing section, of means whereby said carriages can be withdrawn and replaced alternately, lifts for moving the reels to and from the

carriages, standards on said carriages for revolubly supporting the spindles of the 25 reels and lateral projections on said standards along which the spindles of the reels can be rolled to and from the lifts.

21. In a printing machine, the combination with two reel carriages for each printing section, of means whereby said carriages can be withdrawn and replaced alternately, a pivoted latch lever on each carriage, an inclined or conical projection on the machine frame, a brake tension device comprising 30 35 a cylinder and a piston, a rod attached to the piston, and a toe piece at the free end of said rod adapted to coöperate with said latch lever.

In testimony whereof we affix our signatures in presence of two witnesses.

OTTO LEONARD RAABE.
ARTHUR TERREY.
